W. K. HENRY

REMOTE THERMALLY CONTROLLED DOOR CLOSER

Filed Nov. 11, 1922

18 28 20 WILLIAM K. HENRY
By his Attorney
Berthold Monroe

UNITED STATES PATENT OFFICE.

WILLIAM K. HENRY, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

REMOTE THERMALLY-CONTROLLED DOOR CLOSER.

Application filed November 11, 1922. Serial No. 600,261.

To all whom it may concern:

Be it known that I, WILLIAM K. HENRY, a citizen of the United States, residing at New Britain, county of Hartford, State of Connecticut, have invented a certain new and useful Improvement in Remote Thermally-Controlled Door Closers, of which the following is a full, clear, and exact description.

10 My invention relates to door closers, and more particularly to door closing checks of the type which are capable of holding the door open when the door is opened to a predetermined degree, and of releasing and 15 closing the door in the event of fire; and has for its principal object to provide a novel and improved door check of this type which is simple, strong and durable in construction, and reliable in operation.

20 The several features of the invention will be clearly understood from the following description and accompanying drawings, in which,

Figure 1 is a plan view of a door check 25 embodying the features of the invention in their preferred form, the door check being shown applied to a swinging door and the door case being shown in section;

Fig. 2 is a similar view but with the door 30 shown open;

Fig. 3 is a side elevation of the same, and in addition showing a portion of the ceiling of the room in section;

Fig. 4 is a detail sectional view, on an 35 enlarged scale and partly in elevation, taken on the line 4-4 of Fig. 2; and

Figs. 5 and 6 are detail sectional views 40 taken on the lines 5-5 and 6-6, respectively, of Fig. 4.

The door check illustrated in the drawings is shown applied to a swinging door 2 and a door case 4. The door check comprises a casing 6 which is secured to the door. The casing 6 is of a common construction and contains a helical spring (not shown) surrounding an arbor or shaft 8. The spring is held under proper tension by means of a locking disk 10 surrounding the upper end of the shaft, and a pawl 12 carried by an actuating arm 14 and adapted to engage one of the notches 13 in the periphery of the disk. The actuating arm 14 is secured at one end to the upper end 45 of the shaft 8 above the locking disk 10.

A longitudinally adjustable link 16 is pivotally mounted at one end on a pivot pin 15 secured to the free end of the arm, and the other end of the link is pivotally connected with a bracket 17 which is adapted to be attached to the door case. With this 55 construction, upon opening the door the spring actuated arm 14 will tend to close the door and to hold the door closed in the usual manner.

In the illustrated construction means is 60 provided for holding the door open when it is fully opened or opened to a predetermined degree. To provide for this a chamber 18 is formed on the under side of the arm 14 and extends longitudinally of 65 the arm. The end portion of the interior of the chamber 18 directed toward the axis of the shaft 8 is reduced in diameter to provide a bearing for a slidable detent 20. An anti-friction roll 22, mounted on the outer 70 end of the detent 20, is adapted to enter a cooperating locking recess or notch 24 in a projection 26 on the casing 6 when the door is swung open. The detent 20 is provided with a head 28 that cooperates with a 75 shoulder 30 on the interior of the chamber 18 to limit the extent of the outward movement of the detent. The head 28 is U-shaped and the interior of the chamber 18 back of the shoulder 30 is of a corresponding 80 shape so as to cooperate therewith to prevent the detent from turning, which insures the roll 22 being held in proper angular 85 position at all times so as to enable it to properly engage the notch in the projection 90 26. The detent 20 is urged outwardly by means of a coiled spring 32 arranged in the chamber 18. The coiled spring 32 is engaged by an abutment or nut 34 which substantially fits the U-shaped portion of the interior of the chamber 18 so as to be held 95 from rotation but permitting longitudinal movement thereof in the chamber. An adjusting screw 36 is screw-threaded through the nut 34 and its outer end is provided with a head 37. Means is provided for holding the adjusting screw from axial movement, but permitting rotary movement thereof to enable the spring 32 to be 100 adjusted, the screw 36 and the nut 34 constituting an adjustable abutment for the spring.

Except as hereinafter described, the parts

above referred to may be and preferably are the same as the corresponding parts of the door check illustrated and described in my copending application, filed of even date 5 herewith Serial Number 600,260.

In the illustrated construction thermally controlled means is provided which is adapted to be connected with the ceiling of the room in which the door check is located for 10 holding the moveable abutment comprising the adjusting screw 36 from outward movement under normal conditions so as to maintain the detent spring 32 under tension, but which when the temperature about the upper part of the room reaches a predetermined degree, as in the event of fire, releases the adjusting screw 36 so as to relieve the tension of the spring 34, thus enabling the spring actuated arm 14 to close the door. 15 By my invention this ceiling connection is accomplished in spite of the fact that the detent is mounted on the actuating arm 14. As shown, this connecting means comprises a lever 38 which is pivotally mounted on a 20 screw 40 on the under side of the spring actuated arm 14. One end of the lever 38 is provided with a cam surface 41 which is adapted to engage the end of the adjusting screw head 37. The other arm of the lever 38 projects outwardly and a link 42 connects the outer end of this arm with a chain 44 that passes over a guide roll 46 which is mounted on the pivot pin 15 that forms the 25 pivotal connection between the spring actuated arm 14 and the link 16. The other end of the chain 44 is connected through an adjustable turn-buckle 48 with one end of a fusible link 50. The other end of the fusible link is connected with one end of a cable or 30 wire 52 that is threaded through a guiding eyelet 54 secured to the bracket 17. The cable 52 extends upwardly from the eyelet 54, and its upper end is secured to one end of a fusible link 56. The fusible link 56 is 35 arranged close to the ceiling and its upper end is connected by a cable 58 and a screw eye 60 with the ceiling.

With this construction it will be apparent that under normal conditions the cam lever 38 will be held in position to maintain the detent spring 32 under proper tension so that the detent 20 will cooperate with the notch 24 to hold the door open when the door is fully opened or opened to a predetermined degree, and to release the spring actuated arm when the door is being closed; that upon either one, or both, of the fusible links 50 and 56 being fused, that the lever 38 will be released, and thus relieving the tension of the spring 32 and permitting the spring actuated arm 14 to immediately close the door. It may be noted that the thermally controlled means connected with the lever arm 38 is so constructed and arranged 50 that under normal conditions the door may

be opened and closed without separating or materially disturbing the relative position of the component parts thereof. The detent spring 32 may be adjusted either by means of the screw 36 or by the turn-buckle 48, 70 and the turn-buckle may also be employed to tighten the thermally controlled means.

As will be evident to those skilled in the art, my invention permits of various modifications without departing from the spirit 75 thereof or the scope of the appended claims.

What I claim is:

1. A door check having, in combination, a casing for attachment to the door, a spring actuated arm movable horizontally about the vertical axis of said casing, a link pivotally connected with said arm for connecting said arm to the door case, a slideable detent mounted on said arm and having its outer end arranged to engage an abutment on said casing when the door is open, a spring for urging said detent outwardly, means comprising a lever pivoted on said arm for maintaining said spring under tension when the lever is held in a predetermined angular position, a 80 guide carried by said spring actuated arm and having its axis in alignment with the axis of the pivotal connection between said arm and said link, a guiding member arranged adjacent the axis of the pivotal connection of said link and door case, and a thermally controlled flexible connection passing over said guide and guiding member and having one end secured to said lever and its other end adapted to be secured to the 85 ceiling for holding said lever in said predetermined position.

2. A door check having, in combination, a casing for attachment to the door, a spring actuated arm movable horizontally about the vertical axis of said casing, a link having one end pivotally connected with said arm and its other end pivotally connected with the door case, a detent mounted on said arm and having one end arranged to engage an abutment on said casing when the door is open, a spring for urging said detent in a direction 100 to engage said abutment, means comprising a lever pivoted on said arm for maintaining said spring under tension when the lever is held in a predetermined angular position, and a thermally controlled flexible connection extending from said lever about the axis of said pivotal connection between said link and spring actuated arm and to a point 105 arranged adjacent the pivotal connection of said link and door case and adapted to be connected with the ceiling for holding said lever in said position independently of the movement of said spring actuated arm in 110 either direction.

3. A door check having, in combination, a casing for attachment to the door, a spring actuated arm movable horizontally about the vertical axis of said casing, a link having 115

one end pivotally connected with said arm and its other end pivotally connected with the door case, a detent mounted on said arm and having one end arranged to engage an abutment on said casing when the door is open, a spring for pressing said detent in a direction to engage said abutment, means comprising a member mounted on said arm for maintaining said spring under tension when said member is held in a predetermined position on the arm, and a thermally controlled flexible connection connected with

said spring tensioning member and extending about a point arranged adjacent the axis of said pivotal connection between said link and spring actuated arm and to a point arranged adjacent the pivotal connection of said link and door case, and adapted to be connected with the ceiling for holding said spring tensioning member in said position independently of the movement of said spring actuated arm in either direction. 15 20

WILLIAM K. HENRY.
